[57] CLAIM

The ornamental design for ring nut for garden hose connector, substantially as shown and described.

DESCRIPTION

FIG. 1 is a front perspective view of a ring nut for a garden hose connector showing my new design;
FIG. 2 is a rear perspective view thereof;
FIG. 3 is a front elevational view thereof;
FIG. 4 is a side elevational view thereof, the other sides being the same as the side shown; and
FIG. 5 is a rear elevational view thereof.

*Fig. 1.**Fig. 2.**Fig. 3.**Fig. 4.**Fig. 5.*
